ABSTRACT

An analogue gate with a short response time comprises a field-effect transistor whose source or drain is connected to the input, the other electrode to the output. It is triggered from the blocking to the conducting state by a follower which places the gate voltage at the same level as the source voltage and is blocked by means which establish a conductive path from the gate to a suitable voltage source.

6 Claims, 3 Drawing Figures

ANALOGUE GATES

The present invention relates to an analogue gate, that is to say an electrical circuit with an input and an output and an electronic control element. The application to this control element of a voltage that can adopt two logic levels referred to as 0 and 1, enables said circuit to be given either a substantially 0 impedance (output voltage equals the input voltage) or a very high impedance (output voltage 0), the input voltage varying continuously between two given extreme values.

It is well known to manufacture circuits of this kind by means of field-effect transistors, these transistors being rendered conductive or being blocked, by the application of an appropriate voltage to their control gate. The main drawback of these circuits is that they have a substantial response time. As a matter of fact, the gate does not generally have any conductive path for evacuating the charges of the gate-drain capacitance, when the element is triggered from the conductive state to the blocked state.

The object of the present invention is an analogue gate comprising a field-effect transistor which is free of these drawbacks.

The analogue gate in accordance with the invention comprises a first field-effect transistor, having a source receiving the input voltage, a drain supplying the output voltage and a gate, a switch, having one output connected to said transistor gate, a first input connected to a fixed potential capable of blocking said transistor, and a second input; a voltage follower, having an input connected to said drain, an output connected to said second switch input; said switch having a control input for switching at will, said two switch inputs to said switch output.

The present invention will be better understood from a consideration of the following description and by reference to the attached drawings in which:

FIG. 1 illustrates a block circuit diagram of the device in accordance with the invention.

FIG. 2 illustrates an example of the invention.

FIG. 3 illustrates the circuit of FIG. 2 formed in integrated fashion on a single substrate.

In FIG. 1, the field-effect transistor T_1 which is the main element of the analogue gate, has its source connected to the input terminal V_E of the device. To this input terminal is applied a voltage which varies continuously between two predetermined values, for example -2 volts and +2 volts. Its drain is connected to the output terminal S which is in turn earthed across a load C . Its drain is connected on the other hand to the input of the voltage-follower T_2 whose output reconstitutes the voltage at S , thus operates as an impedance-matching device having a high input impedance and a low output impedance.

The output of the follower is connected to an input E_1 of a switch I whose other input E_0 is connected to the negative pole P of a voltage source, which when applied to the gate of the transistor, is capable of blocking the transistor T_1 . The switch I has a control input E_c supplied with a two-level voltage which respectively places it in two states respectively indicated by 0 and 1.

In the 0 state, the input E_0 of the switch is connected to the output G , whilst in the 1 state, the input E_1 of the switch is connected to the output G .

The operation of the system is as follows:

a. state 1: the input E_1 is connected to the gate of the transistor T_1 . The result is that this gate is at the drain potential of the same transistor. Whatever the type of transistor involved, provided that its conduction channel exists at a potential difference of $V_{ds} = 0$ (transistor of the depletion type), the transistor will be conductive and $V_S = V_E$.

b. state 0: the output G is connected to the input E_0 , and the gate is connected to the bias source P whose potential is chosen, in terms of polarity and amplitude, to be sufficiently high in order to block the transistor. When transistor is triggered from the conductive state to the blocked state, the gate-drain capacitance of the transistor discharges across the circuit comprising the amplifier T_2 , the switch G and the ground. Transistors currently being manufactured by microelectronic techniques, have a gate-drain capacitance which is sufficiently low for their charging and discharging time to be neglected, whatever the resistance across which said charging or discharging takes place.

FIG. 2 illustrates an embodiment of the device shown in FIG. 1. In this figure, similar references designate similar elements to those shown in FIG. 1; all the field-effect transistors have an N-type channel and are of the depletion type. This circuit can be integrated. The amplifier-follower is a field-effect transistor T_2 whose gate is connected to the drain of the transistor T_1 , the drain to the positive terminal of a battery E_2 , the source to the drain of a transistor T_3 whose gate and source are interconnected and taken together to the negative terminal of a battery E_3 . The transistor T_3 is therefore conductive at all times and can be considered as a variable resistor.

The source of the transistor T_2 also is connected to the drain of a field-effect transistor T_4 the source of which is connected to the gate of the transistor T_1 , the gate to the drain of a transistor T_5 . The drain of the latter transistor is likewise connected to the gate of the transistor T_1 across a resistor R_1 . Its source is connected to negative terminal of the battery E_3 . Its gate is supplied with a two-level control voltage, one of said levels blocking the transistor T_5 and the other driving it conductive.

As outlined hereinabove, in this non-limitative example, all the transistors of the depletion type have N-type channels. The input voltage varies between -2 volts and +2 volts. The battery E_2 supplies 6 volts, the battery E_3 -6 volts. The voltage levels applied to the gate of the transistor T_5 are respectively -6 volts (level 1) and -8 volts (level 0).

The transistor T_5 is therefore conductive when its gate is at level 1 ($V_{gs} = 0$) and is designed for being blocked when its gate is at the level 0 ($V_{gs} = -2$ volts).

Operation of the system is as follows:

a. the transistor T_5 is blocked (level 0). No current flows across the resistor R_1 and the potential difference V_{gs} on the transistor T_4 is 0. The latter transistor is therefore conductive. The transistor T_2 being designed to follow the voltage V_S , its source potential is substantially equal to the source potential of the transistor T_4 . This voltage is applied to the gate of the transistor T_1 , through the medium of the transistor T_4 , so that the transistor T_1 is conductive. The voltage V_S is therefore substantially equal to the input voltage V_E .

b. the transistor T_5 is conductive. The drain voltage V_d of said transistor is therefore around -6 volts.

A current flows across the resistor R_1 and this has the effect of producing a positive potential difference between the gate of the transistor T_4 (potential substantially equal to -6 volts) and the source of said transistor, which potential is equal to $(-6 \text{ volts} + R_1 i)$, i being the current flowing through the resistor.

The transistor therefore tends to block although it retains a certain level of conductivity. The gate of the transistor T_1 is at a potential of -6 volts $+ R_1 i$, that is to say in the order of -4 volts.

Its source voltage being equal to -2 volts at a minimum, and to $+2$ volts at a maximum, it is therefore blocked as well.

It should be pointed out that when the transistor T_1 is triggered from the state 1 to the state 0, in this arrangement, the gate-drain capacitance of the transistor T_1 discharges across the resistor R_1 and the transistor T_5 which is conductive, the transistor T_4 acting as the switch of FIG. 1.

An integrated circuit manufactured using micro components and designed on the basis of the foregoing data, has a response time of some nanoseconds and the absolute value $V_E - V_S$ is less than 40 millivolts, when transistor T_1 is conducting.

FIG. 3 illustrates an integrated embodiment of the circuit shown in FIG. 2, the references employed there designating similar elements to those they designated previously, the substrate being of $P+$ type, the channels being of N -type and the sources and drains of $N+$ type. The ohmic contacts are of N -type. Sources, gates and drains of each transistor have an index indicating which transistor is involved. The transistor T_1 , whose source S_1 , gate G_1 and drain D_1 can be seen, is U-shaped.

The full lines illustrate the contours of the metallised areas; the chain dotted lines indicate the contours of the sources and drains ($N+$ doped zones), whilst the broken lines indicate the gate contours ($P+$ doped zones), the channels extending beneath the gates being illustrated by sets of dashes separated by three dots. The dashes illustrate the contours of the N doped zones deposited by epitaxy upon the substrate which is of P type. In the illustration, drain and source of the transistor T_1 have been reversed. The drain D_1 extends beneath a metallised area acting as a contact and supplied with the voltage V_E . The source S_1 extends beneath a metallised area which furnishes the voltage V_N . The

gate G_2 is connected to the source S_1 . The electrodes D_4 , D_3 and D_2 are formed in one and the same diffusion operation, as also are the sources S_3 and S_5 . The gate G_5 and the source S_3 are connected by the same metallised area. The resistor R_1 is an N -doped zone. In the figure, the letters M , SD , C , G and N designate respectively the metallised areas (M), the sources (S) and drains (D), the channels (C), the gates (G) and the layers (N).

10 What I claim is:

1. An analogue gate comprising a first field-effect transistor, having a source receiving the input voltage, a drain supplying the output voltage and a gate, a switch, having one output connected to said transistor gate, a first input connected to a fixed potential capable of blocking said transistor, and a second input; a voltage follower, having an input connected to said drain, an output connected to said second switch input; said switch having a control input, for switching at will, said two switch inputs to said switch output.

2. A gate as claimed in claim 1 wherein said switch comprises a second transistor, having a source at a fixed potential, a drain and a gate for receiving a two-level voltage for blocking or unblocking said transistor, a third transistor having a source, a gate and a drain connected to said voltage follower output, said third transistor gate being connected to said second transistor drain, a resistor interconnecting said second transistor drain and said third transistor source.

3. A gate as claimed in claim 2, wherein said voltage follower comprises a fourth transistor having a drain connected to another fixed potential of a polarity opposite to said fixed potential, a gate connected to said first transistor drain, and a source connected to said third transistor drain, and a further resistor for connecting said fourth transistor source to said fixed potential.

4. A gate as claimed in claim 3, wherein said further resistor comprises, a fifth transistor, having a drain connected to said fourth transistor source and a gate and a source interconnected to said fixed potential.

5. A gate as claimed in claim 4, wherein said transistors are of the depletion type and have N -type channels.

6. A gate as claimed in claim 1 having components integrated upon the same substrate.
